Primary Examiner — Patricia Palasik*(74) Attorney, Agent, or Firm* — Andrew Wilford(57) **CLAIM**

The ornamental design for a milling tool, as shown and described.

DESCRIPTION

FIG. 1 is a front elevational view of a first embodiment milling tool formed as a steel disk with edge teeth and a central circular hole;

FIG. 2 is an edge view of the tool of FIG. 1, all edge views being identical;

FIG. 3 is a back elevational view of the milling tool of FIG. 1; FIG. 4 is a front elevational view of a second embodiment of milling tool like that of FIG. 1;

FIG. 5 is an edge view of the tool of FIG. 4, all edge views being identical; and,

FIG. 6 is a back elevational view of the milling tool of FIG. 4.
